5 Claims. (Cl. 260—479)

The present invention relates to new carbamic acid esters which have fungitoxic properties, and to a process for the production thereof.

One object of the present invention consists in disclosing new carbamic acid esters which have fungitoxic properties. Another object consists in providing several processes for the production of these new carbamic acid esters. It is also an object of the invention to provide new agents for combating phytopathogenic fungi. Further objects can be seen from the following description and the examples.

It is already known that substituted phenyl-N,N-dimethyl carbamates have herbicidal properties (cf. U.S. Patent No. 3,933,383), but a fungicidal activity of these substances has hitherto not been known.

It has been found that the new carbamic acid esters of the formula

in which:

R_1 stands for hydrogen, alkyl, alkenyl, alkoxy, dialkylamino, dialkenylamino, alkylmercapto, alkenylmercapto, halogen and/or nitro,

A stands for alkylene with 1 to 10 carbon atoms,

R_2 stands for chlorine, alkoxy, alkylmercapto, cycloalkoxy or a heterocyclic radical, and

n stands for a number from 1 to 5,

have strong fungitoxic properties.

It has also been found that the carbamic acid esters of the Formula I are obtained when, in a manner known as such,

(a) phenols of the general formula

in which R_1 and n have the above meaning, and are reacted with isocyanates of the formula

in which A and R_2 have the above meaning, or

(b) phenols of the Formula II are converted in a first step with phosgene into the corresponding chloroformic acid esters and these are reacted in a second step with amines of the general formula

in which A and R_2 have the above meaning, or

2

(c) phenols of the Formula II are converted in a first step with phosgene into the corresponding bis-phenyl carbonates, and these are reacted in a second step with amines of the Formula IV.

If, for example, 2,4-dichloro-6-nitro-phenol and 1-isocyanato-6-chloro-n-hexane are used as starting materials, the course of the reaction can be illustrated by the following reaction scheme:

The starting materials to be used are clearly characterised by the above Formulae II, III, and IV. In these formulae, R_1 preferably stands for hydrogen, alkyl, alkenyl, alkoxy, dialkylamino and alkylmercapto, each with 1 to 4 carbon atoms in the alkyl radicals, for dialkenylamino and alkenylmercapto, each with 2 to 4 carbon atoms in the alkenyl radicals, as well as for chlorine, bromine and nitro. A chiefly stands for alkylene with 1 to 8 carbon atoms. R_2 preferably stands for chlorine, alkoxy with 1 to 10 carbon atoms, alkylmercapto with 1 to 4 carbon atoms, cycloalkoxy with 5 to 6 ring atoms and heterocyclic radicals with 5 to 6 ring atoms which preferably contain oxygen, nitrogen or sulphur.

As examples of phenols which can be used according to the invention, there may be mentioned: phenol, 4-methyl-, 3-methyl-4-chloro-, 2-allyl-, 3-methoxy-, 2-chloro-, 3-chloro-, 4-chloro-, 2,4-dichloro-, 2,4-dichloro-, 6-nitro-, 2,4,6-trichloro-, pentachloro-, 2-chloro-4-nitro-, 3-methyl-4-dimethylamino-, 2-diallylaminoo-, 4-methylmercapto-, 3-methyl-4-methylmercapto-, 3,5-dimethyl-4-methylmercapto-, 2-isopropyl-4-methylmercapto-, 3-methyl-4-allylmercapto-phenol.

Examples of isocyanates or amines to be used according to the invention are 1-chloroethyl-2-, 1-chlorobutoxypropyl-, 1-chloro-n-hexyl-6-, methoxymethyl-, methoxypropyl-, ethoxypropyl-, sec. butoxypropyl-, cyclohexoxypropyl-, isopropoxypropyl-, 2-ethylhexoxypropyl-, methylmercaptoethyl-, ethylmercaptopropyl-isocyanate or -amine.

The process (a) is expediently carried out in the presence of inert organic solvents within a temperature range between -50 and $+150^\circ\text{C}$., and bases, preferably tertiary amines such as triethylamine and pyridine, are optionally added as catalysts.

The first step of process (b) is expediently carried out at pH values below 6 in aqueous or alcoholic solvents within a temperature range between about -50 and $+150^\circ\text{C}$. The second step of this process is expediently performed in the presence of inert organic solvents within a temperature range of about -20 to $+120^\circ\text{C}$.

The first step of process (c) is expediently carried out at pH values between 6 and 9 in the presence of inert organic solvents, with the addition of an inorganic agent splitting off acid, such as a sodium hydroxide solution, at temperatures between 0 and 100° C. The second step of this process is expediently performed in the presence of inert organic solvents at temperatures between 50 and 150° C.

Suitable inert organic solvents are, for example, hydrocarbons, such as benzine and benzene; chlorinated hydrocarbons, such as methylene chloride and dichlorobenzene; ethers, such as diethyl ether and dioxane; ketones, such as acetone and cyclohexanone, as well as acetonitrile and dimethyl formamide. However, it is also possible to work without a solvent.

For carrying out the processes according to the invention, the reaction components are used in about equimolar amounts, but the phosgene can also be employed in excess. The reaction is carried out in the usual manner. Working up is performed by known methods.

The compounds according to the invention have a strong fungitoxic effect and are distinguished by a broad spectrum of activity. Due to their low toxicity towards warm-blooded animals, they are suitable for combating undesirable fungus growth. Their good compatibility with higher plants enables them to be used as plant protective agents against fungus diseases.

The compounds according to the invention have proved especially satisfactory for controlling rice diseases. They have an excellent protective effect when combating *Piricularia oryzae* in rice.

They also have a good fungitoxic activity against other fungi causing rice diseases, such as *Cochliobolus miyabeanus* and *Corticium sasakii*.

The substances according to the invention also have an especially good activity against a number of other fungi, such as species of *Mycosphaerella*, *Cercospora*, *Corticium*, *Alternaria*, *Septoria*, and against *Botrytis cinerea*.

The compounds according to the invention also have a fungitoxic activity against fungi which attack the plant from the soil and sometimes cause tracheomycoses, such as *Phialophora cinerescens*, *Verticillium alboatrum*, *Fusarium oxysp.f.cubense*, *Fusarium oxysp.f.dianthi*.

Since the compounds according to the invention, as leaf fungicides, have mainly a protective effect, a mixture with curative agents is advantageous. Organic mercury compounds, such as phenyl-mercury acetate, and also antibiotics, such as Plasticidin S, are suitable for this purpose. By adding the compounds according to the invention, a substantial reduction of the mercury content can be achieved in the mixed preparation. The disadvantages occurring when organic mercury compounds are used by themselves, such as the toxicity towards warm-blooded animals, can thus be reduced. By combining preparations of protective and of curative effect, as in the mixture mentioned above, an increased effectiveness can be attained.

The compounds according to the invention can be transformed into the usual formulations, such as emulsifiable concentrates, spray powders, pastes, soluble powders, dusts and granulates. These are prepared in known manner, for example by extending the active ingredients with solvents and/or carriers, if desired with the use of emulsifiers and/or dispersing agents (cf. Agricultural Chemicals, March 1960, pages 35-38). Suitable auxiliaries for this purpose are mainly solvents, such as aromatics (e.g. xylene, benzene), chlorinated aromatics (e.g. chlorobenzenes), paraffins (e.g. petroleum fractions), alcohols (e.g. methanol, butanol), amines (e.g. ethanolamine, dimethyl formamide), and water; carriers, such as natural rock flours (e.g. kaolins, aluminas, talc, chalk), and ground synthetic stone (e.g. highly dispersed silicic acid, silicates); emulsifiers, such as non-ionic and anionic emulsifiers (e.g. polyoxyethylene-fatty acid esters, polyoxyethylene-fatty alcohol ethers, alkylsulphonates and aryl-

sulphonates), and dispersing agents, such as lignin, sulphite waste liquors and methyl cellulose.

The compounds according to the invention can be present in the formulations in admixture with other known active ingredients.

The formulations generally contain between 0.1 and 95, preferably between 0.5 and 90, percent by weight of active compound.

The compounds to be used or their preparations are applied in usual manner, for example by spraying, dusting, sprinkling or atomizing. The active ingredient can be used in concentrations between 0.2 and 0.005%, dependent upon the intended application. In special cases, however, it is possible to exceed or to remain below this range of concentration.

The following examples are given for the purpose of illustrating the invention.

Example A.—*Piricularia* test/liquid preparation of active compound

10 Solvent: 1 part by weight of acetone
Dispersing agent: 0.05 part by weight sodium oleate
Other additives: 0.2 part by weight gelatin
Water: 98.75 parts by weight H₂O

15 The amount of active compound required for the desired concentration of the active compound in the spray liquid is mixed with the stated amount of solvent, and the concentrate obtained is diluted with the stated amount of water containing the stated additives.

20 Thirty rice plants which are about 14 days old, are sprayed with the spray liquid until dripping wet. The plants remain in a greenhouse at temperatures of 22 to 24° C. and at a relative atmospheric humidity of about 70%, until dry. They are then inoculated with an aqueous suspension of 100,000 to 200,000 spores/ml. of *Piricularia oryzae* and placed in a room at 24-26° C. and at a relative atmospheric humidity of 100%.

25 Five days after inoculation, the infestation of all the leaves of the treated plants, which were present at the time of inoculation, are determined as a percentage of the untreated, but also inoculated control plants. 0% means that no infestation occurred, 100% means that the infestation is exactly the same as that of the control plants.

30 The active compounds, their concentrations and the results obtained can be seen from the table below (Table 1).

Example B.—*Piricularia* test/solid preparation of active compound

35 Solvent: 10 parts by weight acetone
Dust Base: 100 parts by weight—
0.5% Mg. stearate
4.0% silicic acid
0.5% Mg. stearate

40 The amount of active compound required for the desired concentration of the active compound in the dusting agent is mixed with the stated amount of solvent, and the concentrate obtained is triturated in a mortar with the stated amount of dust base until the solvent has evaporated.

45 Thirty rice plants which are about 14 days old are dusted with this agent. They are then inoculated with an aqueous suspension of 100,000 to 200,000 spores/ml. of *Piricularia oryzae* and placed in a room at 24-26° C. and at a relative atmospheric humidity of 100%.

50 Five days after inoculation, the infestation of all the leaves of the treated plants, which were present at the time of inoculation, are determined as a percentage of the untreated, but also inoculated control plants. 0% means that no infestation occurred, and 100% means that the infestation is exactly the same as that of the control plants.

55 The active compounds, their concentrations and the results obtained can be seen from the following table.

Piricularia test:
Liquid preparation of active compound—1
Solid preparation of active compound—s

TABLE 1

Active compound	Preparation	Infestation in percent of the infestation of the untreated control at a concentration of (percent)			
		0.1	0.05	0.01	0.005
	1 s	0	20	22	-----
	1 s	13	75	54	-----
	1 s	10	25	75	-----
	1 s	62	100	100	-----
	1 s	0	75	28	-----

Example C.—Mycelium growth test

Nutrient medium:	Parts by weight
Agar-agar	20
Malt extract	30
Distilled water	950

Ratio of solvent to nutrient medium:

Acetone	2
Nutrient medium	100

The amount of active compound required for the desired concentration of the active compound in the nutrient medium is mixed with the stated amount of solvent. The concentrate obtained is thoroughly mixed in the stated ratio with the liquid nutrient medium the temperature of which is about 42° C., and poured into Petri dishes of 9 cm. diameter. Control dishes without the active compound are also provided.

35 When the agar medium has cooled and solidified, the dishes are inoculated with the fungi specified in the table, and incubated at about 21° C.

Evaluation is carried out after 4 to 10 days, dependent upon the rate of growth of the fungi. For evaluation, 40 the mycelium growth on the treated nutrient media is compared with the growth on the control medium. The evaluation of the mycelium growth is made as follows:

- 0—no mycelium growth
- 1—very strong inhibition of growth
- 2—medium inhibition of growth
- 3—slight inhibition of growth
- 4—growth equal to that of untreated control.

50 The active compounds, their concentrations and the results obtained can be seen from the following table (Table 2).

EXAMPLE 1

24.5 grams of 2,4-dichlorophenol are dissolved in 200 ml. of a mixture of acetone and methylene chloride (molecular ratio 1:1); 24.0 g. of isopropoxy-propyl isocyanate and 0.5 ml. of pyridine are added and the mixture is heated at 40° C. for 4 hours. After removal of the solvent in a vacuum, the residual solid substance is recrystallised from ethanol.

Yield: 44.0 g. (95.6% of the theoretical) of 2,4-dichlorophenyl - N - (3-isopropoxy-propyl) carbamate; M.P. 61° C.

EXAMPLE 2

A solution of 20.8 g. of 2,4-dichloro-6-nitro-phenol in 150 ml. of toluene, and a solution of 11 g. of triethylamine in 100 ml. of toluene are simultaneously added dropwise at 5-10° C., while stirring, to a solution of 10 g. of phosgene in 50 ml. of toluene, in such a manner that the phenolic solution is added more rapidly. The corresponding chloroformic acid phenyl ester is formed. When the dropwise addition is completed, stirring is continued for 30 minutes, and the excess phosgene is removed in a vacuum. After the mixture is filtered off with suction from the precipitated salt, a solution of 20.8 g. of ethoxypropylamine in 50 ml. of toluene is added dropwise at room temperature. After further stirring for two hours and filtering off the ethoxypropylamine hydro-

chloride, the solvent is distilled off. The 2,4-dichloro-6-nitrophenyl-N-(3-ethoxypropyl) carbamate is obtained in the form of pale yellowish crystals.

Yield: 29.0 g. (86.1% of the theoretical), M.P. 83-84° C. (from ethanol).

EXAMPLE 3

31.2 grams of 2,4-dichloro-6-nitro-phenol are dissolved in 200 ml. of benzene, 200 ml. of water are added thereto, and 6.2 g. of sodium hydroxide in 50 ml. of water are simultaneously added dropwise while continuously introducing phosgene. The introduction of phosgene is continued until the reaction is acidic.

The organic phase is separated, and 45.0 g. of 3-isopropoxy-propylamine are added dropwise at 0° to +15° C. After further stirring for 4 hours, the reaction solution is poured into water, the benzene is separated, washed once with 100 ml. of 1 N NaOH and twice with 100 ml. of water, then dried and concentrated.

Yield of 2,4-dichloro-6-nitro-phenyl-N-(3-isopropoxy-propyl) carbamate: 48.5 g. (92.0% of the theoretical), M.P. 79-80° C.

EXAMPLE 4

In analogy with the methods described above, the following carbamic acid esters are obtained in good yields:

2,4-dichlorophenyl - N-(6-chloro-n-hexyl) carbamate: M.P. 55-56° C.

9

2,4 - dichloro - 6 - nitro-phenyl-N-(6-chloro-n-hexyl) carbamate; M.P. 68-69° C.

3 - chlorophenyl - N - (2-ethylmercapto-ethyl) carbamate; M.P. 47-49° C.

2,4,6 - trichloro - phenyl - N - (3-isopropoxy-propyl) carbamate; M.P. 69° C.

3 - chloro - 4 - nitro-phenyl-N-(6-chloro-n-hexyl) carbamate; M.P. 58-59° C.

2,4,5 - trichloro - phenyl-N-(3-sec.butoxy-propyl)-carbamate; M.P. 42° C.

2 - chloro - 4,6 - dinitro-phenyl-N-[3-(2-ethyl)-hexoxy-propyl] carbamate; M.P. 53-55° C.

2,4,6 - trichloro - phenyl-N-(3-isobutoxypropyl) carbamate; M.P. 54-56° C.

2,4 - dichloro - phenyl-N-(2-ethylmercapto-ethyl) carbamate; M.P. 67-68° C.

3 - chloro - phenyl-N-(3-ethoxypropyl) carbamate; pale viscous liquid; not distillable; C12H16ClNO3 (257.73). Calculated: N, 5.45%. Found: N, 5.59%.

2,4 - dichloro - 6 nitro - phenyl-N-methoxymethyl carbamate; M.P. 116° C.

10

4-methyl-phenyl - N - (3 - tetrahydro - furfuroxypropyl) carbamate; colourless oil.

Calculated: N, 4.8%. Found: N, 4.6%.

15 2-N,N - diallylamino-phenyl - N - (3-isopropoxypropyl) carbamate; yellow oil.

Calculated: N, 8.4%. Found: N, 8.3%.

25 3-methyl - 4 - dimethylamino - phenyl-N-(2-methylmercapto-ethyl) carbamate; yellow liquid.

Calculated: N, 10.5%. Found: N, 10.0%.

2-nitro - 4 - methyl-phenyl - N - (3-isopropoxypropyl) carbamate; M.P. 60° C.

40 3-methylmercapto - 4 - nitro-phenyl - N - [3-(2-ethyl)-hexoxy-propyl]-carbamate; brown oil.

Calculated: N, 7.0%. Found: N, 7.0%.

3-methyl - 4 - methylmercapto-phenyl - N - (2-methyl-mercapto-ethyl) carbamate; M.P. 50° C.

55 4 - methylmercapto - phenyl - N - (3-methoxy - propyl) carbamate; M.P. 61° C.

3,5-dimethyl - 4 - methylmercapto-phenyl - N - (2-methyl-mercapto-ethyl) carbamate; M.P. 67° C.

phenyl-N-(3-methoxy-propyl) carbamate; viscous oil.

Calculated: N, 6.59%. Found: N, 6.12%.

4-methoxy-phenyl - N - (3-methoxy-propyl) carbamate; M.P. 47° C.

11

(22)

2,4 - dichloro - 6 - nitro - phenyl - N - (2-chloro-ethyl) carbamate; M.P. 142° C.

(23)

2,4,6-trichloro-phenyl - N - [3-(2-methyl)-cyclohexoxy-propyl] carbamate; M.P. 61° C.

(24)

3,5-dimethyl - 4 - allylmercapto-phenyl - N - (2-methylmercapto-ethyl) carbamate; M.P. 45° C.

(25)

2-sec.butenyl - 4 - methyl-phenyl - N - (3-ethoxy-propyl) carbamate; colourless oil.

Calculated: C, 69.3%; H, 8.3%; N, 5.1%. Found: C, 69.24%; H, 8.44%; N, 5.12%.

We claim:

1. A compound of the formula

wherein D is alkylene of 1-8 carbon atoms and R3 is a member selected from the group consisting of alkoxy of 1-10 carbon atoms, chloro, cycloalkoxy of 5-6 carbon atoms in the ring, alkyl mercapto of 1-4 carbon atoms and

12

2. The compound of the formula

in which:

D is alkylene of 1-8 carbon atoms; and
R4 is alkoxy of 1-10 carbon atoms.

3. The compound of the formula

4. The carbamic acid ester of the formula

5. The carbamic acid ester of the formula
